his Attorney

UNITED STATES PATENT OFFICE.

CHARLES S. BUSHNELL, OF ROCHESTER, NEW YORK, ASSIGNOR TO GENERAL RAILWAY SIGNAL COMPANY, OF ROCHESTER, NEW YORK.

TRACK ELEMENT FOR INTERMITTENT INDUCTIVE TRAIN-CONTROL SYSTEMS.

Application filed November 27, 1925. Serial No. 71,750.

This invention relates to automatic train control and more particularly concerns track-way influence communicating means for an automatic train control system of the intermittent inductive type.

In one type of the intermittent inductive train control system, influences are communicated from the trackway to a moving vehicle by means of a change in the reluctance of a magnetic circuit in a car-carried receiving device which occurs when such device passes in close proximity to magnetic bodies or inductors located at spaced points along the trackway. In a system of this type, a restrictive or retarding effect, causing an automatic brake application or other suitable restriction, is produced when the above mentioned influence is transmitted. In order to control the transmission of this retarding influence in accordance with traffic conditions, a coil or winding is provided on the inductor which acts when short circuited to choke or suppress the magnetic flux therethrough, the circuit through this coil being controlled by suitable track relay or signal controlled contacts.

The magnetic structure or inductor is necessarily located along the trackway in close proximity to the track rails and is therefore exposed to the action of the elements and to the possibility of injury from dragging equipment on trains. For this reason the inductor must be protected by a suitably substantial housing which may be conveniently mounted near the track rails. As the air gap through which the inductive impulse acts must be necessarily rather large due to the clearance which must be maintained, the magnetic circuit of the inductor must have a low reluctance, and all eddy current or other core losses in the inductor structure or in the housing must be reduced to a minimum. As the restrictive or stopping impulse is transmitted when the inductor winding is open circuited, the lead wires connected to this winding must be suitably protected against possible cross connection.

With the above and other considerations in mind it is proposed, in accordance with the present invention to provide a trackway inductor for intermittent inductive train control systems which has a magnetic circuit of low reluctance, which is provided with a suitable winding and which is enclosed in a substantial housing shaped to facilitate the

mounting thereof along the trackway and to protect the inductor from injury; and to provide suitable protective means for enclosing the wires leading to the inductor winding.

Other objects, advantages and characteristic features of the invention will become apparent as the description thereof progresses.

In describing the invention in detail, reference will be made to the accompanying drawings in which:

Figure 1 is a top plan view of the inductor structure secured to the several ties of a railroad trackway, certain portions of the casing being broken away to show the interior construction;

Figure 2 is a side view of the housed inductor, half of this view being in section;

Figure 3 is a section taken on the line 3—3 of Fig. 1 and viewed in the direction of the arrows; and

Figure 4 is a section taken on the line 4—4 of Fig. 1 and viewed in the direction of the arrows.

Referring to the drawing, the housed inductor structure of the present invention comprises in a general way a casing 1 enclosing a core structure 2 having a winding 3 thereon. The core structure 2 together with the winding 3 are identical with the core structure and winding shown and described in my copending application Serial #694,993, filed February 25, 1924, and for this reason these parts will be described in a brief manner only in the present application.

The core structure 2 is of general U-shape, and is formed of laminated magnetic material. The laminae used in forming the core have their back yoke portions formed in different widths and are stacked to give the back yoke a cruciform cross section as clearly shown in Fig. 4, the end portions of all of the laminae extending upwardly to form the rectangular upstanding legs 4 of the core. In the corners, between the projecting ends of the cruciform back yoke are provided quarter round strips constructed of suitable insulating material, such as wood, so that the yoke together with the strips 5 is of rectangular cross section having rounded corners. The laminae and the strips 5 are secured together at the ends of the back yoke by the clamping blocks 6, these blocks also serving as end supports for the winding 3.

The upstanding end portions or legs 4 of the core structure are flared apart and a wooden block 7 is inserted therebetween, being clamped in place by the bolts 8 passing through the side plates 9. The pole pieces 10 are secured to the ends of the upstanding legs 4 of the core 2 by the bolts 11 passing through the blocks 7 and the plates 12.

10 The casing 1 is of general U-shaped longitudinal cross section as shown, having ramped or inclined ends 13 and a central portion having a horizontal plane upper surface therebetween. The casing, which is 15 made of bronze, brass, or some other suitable non-magnetic metal, is preferably cast in a single piece to simplify its construction and to provide a surface which will readily withstand and ward off blows from dragging 20 or projecting vehicle apparatus. The ramped ends 13 of the casing 1 are suitably braced or strengthened by the integral webs 14 and 15 and are provided with outwardly projecting integral lugs or flanges 16 having 25 holes 17 therein to receive the bolts or lag screws 18 whereby the casing is secured to the several ties 19 of a railroad trackway. The casing 1 is preferably made of such length, and the lugs 16 are so spaced thereon 30 that the holes 17 will cooperate with the ties 19 which in practice are spaced at fixed and predetermined distances. The extremities of the ramped ends 13 of the casing are preferably rounded as shown, and are formed 35 to extend beyond and below the ties 19 so that there is little or no danger of the casing being torn from place by dragging vehicle equipment. In practice, the casing is 40 preferably mounted outside of the track rails and parallel thereto.

The casing 1 is provided with two aligned openings, 20 and 21 located at the extreme ends of the plane upper surface thereof and extending the entire width of the casing. 45 The pole pieces 10 of the core structure 2 are supported in the openings 20 and 21 on the inwardly projecting flanges 22 as shown in Figs. 2 and 3, and are insulated from electrical contact with the casing 1 by the insulating washers 23 as most clearly shown 50 in Figs. 1 and 2. The washers 23 are substantially rectangular in shape having large openings 24 therein to receive the upstanding ends 4 of the core structure, and are provided 55 with upturned ends 25 to insulate the ends of the pole pieces 10 from the casing 1.

As pointed out in my co-pending application referred to above, the pole pieces 10 are made of a suitable magnetic material 60 and are provided with slots 26, extending from one edge thereof toward the center to a point where the core structure 4 engages the pole piece. These slots 26 serve to prevent the flow of eddy currents in the pole pieces in 65 a circular path around the core structure. In

the present invention, the slots 26 are filled by strips of insulating material 27 which are forced into these slots and frictionally held in place. These insulating strips 27 prevent the entrance of dirt, water, cinders, or other foreign matter to the interior of the casing 1, and also prevent the possibility of an electrical circuit being established across the slots 26 by small particles of conducting material which might collect in 75 these slots.

The plane upper surface of the casing 1 is provided with slot 28 extending longitudinally along the center thereof and connecting the openings 20 and 21. This slot 80 serves to prevent the flow of eddy currents in a closed circuit through the casing around the pole pieces 10. A strip of insulating material 29 is inserted in the slot 28, which strip is turned over within the casing and is riveted to the inner surface thereof by the rivets 30 as clearly shown in Fig. 4.

The casing 1 is of substantially inverted U-shaped cross section in its central portion, having downwardly extending side walls 31 and end walls 32 as shown in Figs. 2 and 4. The open lower side of the central portion of the casing 1 is closed by a cover portion 33 of general U-shaped cross section, made of a suitable non-magnetic metal such as 90 cast aluminum. The cover 33 is provided with outwardly extending flanges 34 at its upper edges, these flanges being arranged to engage the downwardly extending walls 31 and 32 of the casing 1 as clearly shown 95 in Figs. 2 and 4. The cover 33 is securely clamped in engagement with the casing 1 by means of the bolts 11 which hold the pole pieces 10 to the ends of the core structure 4, these bolts being provided with 100 elongated ends 35 which pass through holes near the ends of the cover 33, the lock nuts 36 being provided on the lower ends of the bolts 11 to clamp the cover 33 in place. The bolts 11 are insulated from the cover 33 by 105 means of the insulating bushings 37.

One end of the cover portion 33 is provided with a rectangular pocket or off-set portion 38 as most clearly shown in Fig. 3. This pocket 38 is provided with openings 39 and 40 in the opposite side surfaces thereof, and a junction box 41 is clamped over one of these openings 40 by means of the machine screws 42. A terminal block 43 of insulating material is secured within the junction box 41 by the machine screws 42 as clearly shown in Fig. 1, this block 43 being provided with slots for the reception of the leads 44 of the winding 8, and with suitable terminals 45. The junction box 41 is provided with conduit outlets 46 at its 115 opposite ends, these outlets being provided with suitable conduit connecting clamps as shown. It should be noted that the conduit 120 outlets 46 are as widely separated as pos- 125

sible, thereby separating the two leads connected to the winding 2 and minimizing the possibility of a cross connection between these leads. A removable cover 47 is provided on the junction box 41, being secured to the outer open side thereof by the machine screws 48, and affording easy access to the interior of the box for the purpose of making the necessary electrical connections.

10 The opening 39 in the opposite side of the cover portion 33 from that to which the junction box 41 is connected, is provided to permit the junction box 41 being secured to either side of the inductor casing 1 as desired, this opening 39 being preferably closed when not in use by a removable cover 50 which is held in place by the screws 51.

15 From the description given it will be evident that an extremely simple, rugged and compact construction has been provided for mounting and protecting the trackway inductor and its winding. Eddy current losses in the casing as a result of changes in flux through the core are prevented by the provision of the slots in the casing and the pole pieces, and similar losses in circuits through the core in series with the cover portion 33 or the casing 1 are prevented by the insulating bushings 37 and the insulating washers 23. Because of this insulation 20 of all possible eddy current circuits, the reluctance of the magnetic circuit through the core 1 is reduced to a minimum. The junction box 41 provides a convenient means for connecting the leads to the winding 3 through suitable conduits with the signal or control apparatus. This junction box 25 may be attached on either side of the inductor casing, thus permitting the inductor to be used on either side of the track rails.

30 As the present invention has been shown in a rather specific form and in connection with certain specific details of construction, it should be clearly understood that certain changes, modifications, and improvements 35 may be made without departing from the scope of the invention as defined by the appended claims.

40 What it is desired to secure by Letters Patent is:—

50 1. In an influence communicating device for automatic train control systems, a U-shaped core of magnetic material, a housing for said core comprising a one piece casing having inclined ends, the central portion of said casing being of inverted U-shaped cross section, means for supporting said core from the upper surface of said central portion, and a U-shaped cover portion supported by 55 said core to enclose said core within said central portion.

60 2. In an influence communicating device for automatic train control systems, a U-shaped core of magnetic material, a housing 65 for said core comprising a one piece metallic

casing having inclined ends and a central portion, downwardly extending walls on said central portion, means for supporting said core from the upper surface of said central portion, and a cover secured to said central portion in engagement with said 70 walls and enclosing said core.

3. In an influence communicating device for automatic train control systems, a U-shaped core of magnetic material, a housing 75 for said core comprising a one piece metallic casing having inclined ends, means permitting said casing to be secured to a support, the central portion of said casing being of inverted U-shape with downwardly extending side and end walls, openings in the upper surface of said central portion, means for supporting said core within said central portion from said openings, and a cover engaging said side and end walls and enclosing 80 said core.

4. In an influence communicating device for automatic train control systems, a U-shaped core of magnetic material having upstanding legs and pole pieces secured to 90 said legs, a housing for said core comprising a one piece metallic casing having inclined ends and a central portion, said central portion being of substantially inverted U-shaped cross section, openings in 95 the upper surface of said central portion, means for securing said pole pieces in said openings, a metallic cover for said central portion secured to said core, and means for insulating said core from said casing and 100 from said cover.

5. An influence communicating device for automatic train control systems comprising a U-shaped core of magnetic material, pole pieces secured to the extremities of said 105 core, and a housing for said core comprising a one piece metallic casing having inclined ends, integral means on said ends for permitting said casing to be secured to a support, extensions on said ends adapted to 110 extend below the upper surface of said support, said casing having a central portion of substantially inverted U-shaped cross section, openings in the upper surface of said central portion, means for supporting said 115 core in said central portion with said pole pieces in said openings and flush with the upper surface of said central portion, a winding on said core and a cover secured over the lower part of said central portion and enclosing said core.

6. An inductive influence communicating device for automatic train control systems comprising a U-shaped core of magnetic material having pole pieces, a housing for said core comprising a one piece metallic casing having inclined rounded ends and a hollow central portion, openings in the upper surface of said central portion, said pole pieces being supported in said openings and said 125 130

core extending within said hollow central portion, a coil on said core and a slot in the upper wall of said central portion between said openings.

- 5 7. An inductive influence communicating device for automatic train control systems comprising a U-shaped core of magnetic material having pole pieces, a housing for said core comprising a one piece metallic casing 10 having inclined rounded ends and a central portion of inverted U-shaped cross section, openings in the upper wall of said central portion, said pole pieces being supported in said openings with their upper surfaces flush 15 with the surface of the casing, slots in said pole pieces, a slot in the upper wall of said central portion connecting said openings, and insulating material in said slots.

8. An inductive influence communicating 20 device for automatic train control systems comprising a U-shaped core of magnetic material having pole pieces, a housing for said core comprising a one piece metallic casing having inclined rounded ends and a hollow 25 central portion of inverted U-shaped cross section, said central portion having a plane horizontal upper surface with aligned openings at the opposite ends thereof, a slot in said upper surface connecting said openings, 30 means for supporting said pole pieces in said openings with said core in said hollow central portion, means for electrically insulating said pole pieces from said casing, a lower cover for enclosing said core in said hollow 35 portion, means attached to said core for securing said cover portion to said hollow central portion, and means for electrically insulating said cover from said core.

9. An inductive influence communicating 40 device for automatic train control systems comprising a U-shaped core of magnetic material having pole pieces, slots in said pole pieces filled with insulating material, a housing for said core comprising a one piece metallic casing having aligned openings therein, a slot in said casing connecting said openings and filled with insulating material and means for supporting said pole pieces in said openings with said core extending within 50 in said casing.

10. An inductive influence communicating device for automatic train control systems comprising a U-shaped core of magnetic material, a housing for said core comprising a one piece metallic casing having inclined ends and a hollow central portion of inverted U-shaped cross section, aligned openings in said central portion, pole pieces supported in said aligned openings, a cover 55 for completely enclosing said hollow central portion and means for securing said core to said pole pieces, said means also connecting said cover to said casing.

11. An inductive influence communicating 60 device for automatic train control sys-

tems comprising a U-shaped core of magnetic material, a housing for said core comprising a one piece metallic casing having inclined ends and a hollow central portion of inverted U-shaped cross section, said central portion being open on its lower side and having aligned openings in its upper surface, pole pieces supported in said aligned openings and insulated from said casing, a metallic cover for closing said open lower side of said central portion, and means passing through said hollow central portion for clamping said pole pieces and said cover to said casing, said core being supported within said casing by said means, said means being insulated from said cover.

12. In an inductive communicating device for automatic train control systems, a U-shaped core of laminated magnetic material, a portion of the laminæ of said core being narrower than the remainder along the back yoke of said core and all of said lamina having integral upstanding ends, said laminae being stacked to form a core having a back yoke of cruciform cross section, a winding 90 on said back yoke, a casing for said core having aligned openings therein, pole pieces supported in said openings and means for securing the upstanding ends of said core to said pole pieces whereby said core is supported within said casing.

13. In an inductive influence communicating device for automatic train control systems, a U-shaped core of laminated magnetic material, the laminæ of said core having two different widths along the back yoke thereof and being stacked to provide a back yoke of cruciform cross section, all of the laminae having integral upstanding rectangular ends forming the legs of said core, a one piece hollow metallic casing having openings in the upper surface thereof, pole pieces supported in said openings and insulated from said casing, and a slot in the upper surface of said casing between said openings, said core being supported within said casing from said pole pieces.

14. An inductive influence communicating device for automatic train control systems comprising a U-shaped core of magnetic material having pole pieces, a one piece metallic casing for said core having inclined ends and a hollow central portion, said central portion having openings in the upper surface thereof and being open on its lower side, means for securing said core within said casing with said pole pieces in said openings, a winding on said core, a cover for said open lower side of said casing and a junction box secured to said cover.

15. An inductive influence communicating device for automatic train control systems comprising a U-shaped core of magnetic material having pole pieces, a one piece metallic casing for said core having inclined ends and

- a hollow central portion having an inverted U-shaped cross section, said central portion having aligned openings in the upper surface thereof and being open at the bottom, 35
5 means for supporting said core within said casing with said pole pieces in said openings, a winding on said core, a cover for the bottom of said central portion for completely enclosing said core, a junction box, and 10 means for attaching said junction box to said cover on either side of said casing.
16. An inductive influence communicating device for automatic train control systems comprising a U-shaped core of metallic material having upstanding legs, pole pieces secured to the ends of said legs, the edges of said pole pieces extending laterally beyond said legs, said pole pieces having openings therein preventing the flow of current in 20 said laterally extending edges thereof, a housing for said core comprising a one piece metallic casing having inclined ends, and openings in the upper surface of said casing to receive said pole pieces.
- 25 17. In an inductive influence communicating device for automatic train control systems, a U-shaped core of laminated magnetic material having upstanding legs, each of the laminæ of said core being formed in one 30 piece, a coil on said core, a one piece hollow metallic casing having openings in the upper surface thereof, pole pieces secured in said opening and means for positioning the core within the casing by securing said upstanding legs of said core to said pole pieces.
18. In an inductive influence communicating device for automatic train control systems, a U-shaped core of laminated magnetic material having upstanding legs and a back yoke, a winding on said back yoke, longitudinal strips of insulating material inserted between said winding and said back yoke, a hollow one piece metallic casing for said core and means for supporting said core within said casing.
19. In an inductive influence communicating device for automatic train control systems, a U-shaped core of laminated magnetic material having upstanding legs and a back yoke, a winding on the back yoke, angular longitudinal strips of insulating material inserted between said winding and said back yoke, a hollow one piece metallic casing for said core, and means for supporting said core within said casing.
20. In an inductor, a laminated core of cruciform cross section, elongated angular strips of insulating material fitted into the angles of the core section, and a winding around the core and strips.

In testimony whereof I affix my signature.
CHARLES S. BUSHNELL.
